(57) **CLAIM**

The ornamental design for a hand held surgical instrument, as shown and described.

DESCRIPTION

FIG. 1 is a perspective view of a hand held surgical instrument showing my new design.

FIG. 2 is a top plan view thereof, the bottom plan view being a mirror image thereto.

FIG. 3 is a right side elevational view thereof, the left side elevational view being a mirror image thereto.

FIG. 4 is an end elevational view thereof.

FIG. 5 is an end elevational view thereof, opposite that shown in FIG. 4.

FIG. 6 is an exploded perspective view thereof.

FIG. 7 is a top plan view thereof, the bottom plan view being a mirror image thereto.

FIG. 8 is a right side elevational view thereof, the left side elevational view being a mirror image thereto.

FIG. 9 is an end elevational view thereof; and,

FIG. 10 is an end elevational view thereof, opposite that shown in FIG. 9.
